HEINRICH JUST AND HERMANN HORT, OF ESSEN, GERMANY, ASSIGNORS TO FRIED.
KRUPP AKTIENGESELLSCHAFT, OF ESSEN-ON-THE-RUHR, GERMANY.

FIRE-CONTROL APPARATUS

Application filed December 12, 1927, Serial No. 239,576, and in Germany December 23, 1926.

This invention relates to a fire control apparatus intended for a plurality of naval guns having a common commanding station, on which a sighting device is arranged of a design as described in Letters Patent . . . (patent application Ser. No. 209,119 of July 28, 1927). The object of this invention is to so improve these apparatus, that all the guns of a battery can be fired simultaneously by means 10 of a firing circuit which is closed by the sighting device.

In the drawing is illustrated by way of example a fire control apparatus designed in accordance with the invention. In this drawing:

Figure 1 is a diagrammatic view, looking in the direction of the longitudinal axis of the ship, partly in section, of the fire control apparatus.

Figure 2 is a section on line 2—2 of Figure 1, looking from the top.

A denotes the ship's body and A¹ a pedestal rigidly mounted thereon and arranged at the commanding station. By means of a pivot b¹ an arcuate supporting body B is mounted for rotation on pedestal A¹. This supporting body forms the frame, laterally trainable in the direction of the aim, of the sighting device and has a training gear comprising a hand wheel C mounted on the supporting body B. This training gear is connected to the training gears D of the individual guns, of which only one is shown in the drawing, by means of an electric long distance control device comprising a transmitter c¹ and a number of receivers d¹ corresponding to the number of guns. An adjusting device d² is provided for the receiver d¹ so that an additional angular displacement can be introduced and the guns can be laterally trained individually and separately relative to the lateral training of the sighting device located at the commanding station.

On the arcuate supporting body B, the axis of curvature of which intersects the axis of pivot b¹ in a point 1, a semi-circular adjustable body E is mounted for rotation around said axis of curvature. A hand wheel F² fast on shaft f¹ is provided to effect the adjustment of member E through the intermediation of

pinion F also fast on shaft f¹ and a series of teeth e¹ on member E (see Figure 2). A Cardan ring G is mounted on body E by means of trunnions e², the axis of which passes through point 1 at right angles to the axis of rotation of body E. A casing H is mounted for free swing motion on the Cardan ring G by means of trunnions h¹ the axis of which crosses the axis of the trunnions e² at right angles in point 1. Casing H supports a gyroscope and carries the sighting telescope H². The casing H has mounted on it an arcuate body J adapted to rotate around the axis of the trunnions h¹ and to be adjusted relative to the Cardan ring G by means of a gearing (not shown) in opposition to the elevating motion of the adjusting body E to a firing angle A_m that corresponds to the distance of the aim with a determined average degree of corrosion of the gun barrels, that means with a determined average muzzle velocity. To effect this adjustment an electric follow-the-pointer long distance control apparatus is provided which comprises a transmitter casing K and a wiring L by means of which apparatus the motion of the following pointer is transmitted to the body J. The details of this control apparatus correspond in principle to those of the corresponding apparatus of the sighting device described in the above mentioned patent and need therefore not be described in detail. The arcuate body J carries a roll mark i¹ and a firing tongue i² and a roll mark h³ and a firing tongue h⁴ are arranged on casing H adapted to register with i¹ and tongue i² respectively. The firing tongues i², h⁴ constitute the contactor for a firing circuit common to all the guns, which circuit comprises, besides this contactor that automatically arrives in closing position upon the ship rolling, an additional manipulative contactor.

The shaft f¹ has fixed on it a bevel wheel f³ in mesh with a bevel wheel m¹ fast on a shaft M. The latter is connected with a following pointer arranged on a casing N, of another electric follow-the-pointer long distance control apparatus. A device, comprising a hand wheel N¹, for adjusting additional angles is provided for the electrically adjust-

able pointer belonging to this long distance control apparatus, the adjustment of which pointer is effected in correspondance with the average firing angle A_m . The shaft M is further connected by means of a gear m^2 5 with the transmitter N^3 of a third electric follow-the-pointer long distance apparatus. The transmitter N^3 is electrically connected by wires P to receivers Q , provided for the 10 elevating gear of the individual guns. Each elevating gear comprises a hand wheel S mounted on the carriage R , and a toothed segment t^1 mounted on the cradle of the gun barrel T , a shaft U mounted on the carriage 15 R being positively connected with segment t^1 . Shaft U serves to actuate the following pointer of the receiver Q which is arranged on carriage R . As can be seen from the 20 foregoing, an elevation corresponding to the firing angle A_m can be imparted to the axis of the Cardan trunnions e^2 according to the indications of the receiver N by turning hand wheel F^2 and to each gun barrel according to receiver Q of long distance control 25 apparatus N^2 , P , Q by turning hand wheel S . A device Q^1 intended for the introduction of additional elevating angles is connected to each receiver Q , which device makes it possible for an additional elevation, required due 30 to the degree of corrosion of the respective gun barrel, to be taken into account so that each gun barrel may have imparted to it an elevation that deviates from that of the axis of the Cardan trunnions e^2 by an additional 35 amount of elevation which it requires.

With the aid of the described installation the firing operation takes place in the following manner:

The average firing angle A_m corresponding 40 to the distance of the aim is adjusted from the calculating station of the ship on the receivers of the long distance control apparatus K and N of the commanding station. According to the indications of these receivers, the arcuate body J with the mark i^1 and tongue i^2 is adjusted downwardly by the 45 firing angle through the intermediation of connection L and at the same time upwardly when the hand wheel F^2 , see Fig. 2, is turned 50 to adjust the body E and the Cardan ring by the firing angle A_m . After these adjustments the roll marks i^1, h^3 and the firing 55 tongues i^2, h^4 exactly register, when the ship assumes horizontal floating position and the sighting line of the telescope H^2 is horizontal. Upon the ship rolling, the telescope H^2 is held pointed on the aim horizontally and vertically by the stabilizing effect of the gyroscope and by rocking it by means of 60 hand wheel C . When the aim has such a position, that the sighting line is not exactly horizontal, but deflects from horizontal position by a certain angle, the roll marks i^1, h^3 65 do not register in the horizontal position of the ship, but register only during the rolling

motion of the same. When this is the case, the axis of the Cardan trunnions e^2 which indicates the fundamental direction to be imparted to the gun barrels, irrespective of the position the ship body happens to 70 assume, has the correct position relative to the aim both in elevation and lateral direction. Each gun is thereupon trained by means of the electric follow-the-pointer long distance control apparatus c^1, d^1, D into the 75 same lateral direction as the commanding station and is so adjusted by means of its elevating gear S, t^1 , that the following pointer of the long distance control apparatus N^3 , P, Q, Q^1, t^1, S is opposite to the appurtenant 80 electrically adjusted pointer of the receiver Q . When no additional amount of elevation is to be introduced, the axes of the bores of the gun barrels are then parallel to the axis of the Cardan trunnions e^2 or, when such an 85 additional amount is to be introduced, they deviate from the direction of said latter axis (e^2, e^2) only by the corresponding regulating angle. Thus the axes of the bores of the gun barrels are in correct position as to both elevational and lateral direction. The commander of the battery now observes on the commanding station the roll marks i^1, h^3 . As soon as he has ascertained, that these 90 marks pass past one another upon the ship 95 rolling, and the sighting device and the guns are also in correct position in other respects, then he closes the additional contactor provided in the firing circuit, whereupon all shots of the battery are fired automatically. 100 and simultaneously with the next rolling-through of the firing tongue i^2 . As all gun barrels T are in their correct position with respect to the axis of the Cardan trunnions e^2 and as this Cardan axis assumes its correct position too, all shots are fired with the gun barrels in correct position in space.

When the ship has a list in the direction of the shots, that is, a list angle is to be taken into account, it may happen that the roll marks i^1, h^3 do not travel past one another upon the ship rolling, so that the tongues i^2, h^4 do not register and thus the shots are not fired. In this case the commander introduces on the receiver N by means of the device N^1 an additional counter-list angle in addition to the firing angle A_m indicated by the calculating station, whereupon the operator of the commanding station alters the angular position of the body E by the same additional counter-list angle by means of hand wheel F^2 . This counter-list angle is so determined, that the roll marks i^1, h^3 now travel past one another towards both sides by equal amounts. The transmitter N^3 transmits the additional counter-list angle to the receivers Q of all guns, whereupon this angle is introduced in the guns also. This done, the shots will be fired correctly in the above-described manner.

When the ship rolls only slightly, it may happen that no clear image is obtained whether the roll marks pass one another or not, so that the firing speed is lowered thereby.

5 In this case the commander introduces by uniformly rotating the appurtenant hand wheel N^1 small additional counter-list angles, so that the roll marks now pass one another with certainty. The elevation is 10 then altered both on the sighting device and on the guns in correspondence to these small counter-list angles. As soon as the additional contactor then has been closed and the tongues i^2 , h^4 touch one another, all shots 15 are fired simultaneously.

10 The advantage afforded by the described arrangement primarily resides in the fact, that a reliable and uniform fire government is made possible with the simplest means.

20 Claims:

1. A fire control apparatus for a plurality of guns mounted on a rocking foundation comprising a sighting device having a mounting arranged on said foundation, a sighting 25 means carrier cardanically supported on said mounting, means for adjusting one of the cardanic axes in accordance with the firing angle and a gyroscope rotatable about an axis fixed on said sighting means carrier, an 30 electrical firing device having two contact members adapted to register one with the other when said cardanic axis is properly adjusted for elevation, and means for adjusting each of said guns in accordance with the firing 35 angle in accordance with the adjustment of said cardanic axis.

2. In a fire control apparatus according to claim 1 a long distance control apparatus for adjusting each of the guns for elevation comprising a transmitter associated with said 40 means for adjusting said cardanic axis and a receiver associated with each of the guns.

3. In a fire control apparatus according to claim 1, a long distance control apparatus for 45 adjusting each of the guns for elevation comprising a transmitter associated with said means for adjusting said cardanic axis and a receiver associated with each of the guns, said receivers being provided with means 50 for adjusting additional elevating angles.

4. In a fire control apparatus according to claim 1 a long distance control apparatus having a receiver associated with said means 55 for adjusting said cardanic axis for elevation and another long distance control apparatus for adjusting each of the guns in accordance with the firing angle comprising a transmitter associated with said means for adjusting said cardanic axis and a receiver associated 60 with each of the guns.

5. In a fire control apparatus according to claim 1 a long distance control apparatus comprising a receiver associated with said means for adjusting said cardanic axis and a 65 device associated with said receiver for ad-

justing additional angles of rotation whereby the angle of list can be eliminated.

The foregoing specification signed at Cologne, Germany, this 25th day of November, 1927.
